RADIO TUNING MEANS

Application filed August 27, 1928. Serial No. 302,233.

The present invention relates to radio tuning means.

More particularly the present invention relates to convenient means for selectively tuning in predetermined broadcasting stations by the movement of simple mechanisms.

An object of the present invention is to provide a convenient mechanism applicable to radio receivers as at present commonly used whereby the variable tuning units of such radio receivers may be readily thrown out of service and supplemented by other tuning means selectively responsive to simple switching mechanism.

15 A further object is to provide an improved radio receiver having the advantage that the operator may at will tune either by means of the usual tuning units or by means of tuning elements selectively responsive to simple switching mechanisms.

20 A further object is to provide an improved radio receiver which is relatively cheap to manufacture and having simple tuning elements which may be used in place of the ordinary tuning elements for conveniently tuning said receiver to predetermined broadcasting stations.

25 A further object is to provide an improved radio receiver having the usual variable tuning elements and supplementary relatively simple adjustable tuning elements which upon the actuation of simple switching mechanism may be selectively used instead of said usual variable tuning elements.

30 A further object, supplementing the object last above mentioned, is to provide switching mechanism whereby each of said simple adjustable tuning elements may be adjusted independently of the other simple adjusting tuning elements, whereby the matter of adjustment is simplified.

35 Further objects will appear as the description proceeds.

Referring to the drawings—

40 Figure 1 illustrates an embodiment of the present invention applied to a radio receiver of a design in common use, which radio receiver involves two tuning elements; and

45 Figure 2 shows an embodiment of the present invention applied to a circuit of

usual design having three tuning elements.

There is a need at the present time for a radio receiver which will permit the tuning in of a limited number of predetermined broadcasting stations merely by operation of 55 a button, lever, or equivalent element. It has been suggested that a simple lever mechanism be provided for positively moving the tuning elements of a radio receiver to predetermined positions for tuning in certain 60 predetermined broadcasting stations.

The present invention differs from the idea immediately above referred to. The present invention contemplates means for selectively removing from circuit the usual tuning elements of a radio receiver and inserting into circuit certain simple adjustable tuning elements, which simple adjustable tuning elements may be set at predetermined values. 65

70 Referring to Figure 1, the numerals 1 and 2 indicate inductances and the numerals 3 and 4 indicate tuning condensers forming part of the two tuning units of a radio receiver. The connections of said condensers 3 and 4 to the inductances 1 and 2, respectively, are controlled by the double pole double throw switches 5—5, preferably connected to operate in unison. When the double pole double throw switches 5—5 are in position to connect the variable condensers 3 and 4 to the inductances 1 and 2, respectively, the radio receiver will be connected for its usual operation. The numerals 6—6 indicate an auxiliary circuit adapted to be connected 75

80 to the inductance 1, and the numerals 7—7 indicate an auxiliary circuit adapted to be connected to the inductance 2. When the double pole double throw switches 5—5 are thrown downwardly from the positions shown in Figure 1, the corresponding variable condensers 3 and 4 will be thrown out of cooperative relationship with the corresponding inductances 1 and 2, and circuits 85 90 95 6—6 and circuit 7—7 will be thrown into cooperative relationship with the corresponding inductance 1 or 2.

Connected in parallel across the circuit 6—6 are a plurality of simple adjustable condensers 8—8, each of which is controlled by a switch 9. Similarly connected across the 100

circuit 7-7 are a plurality of simple adjustable condensers 10-10, each of which is controlled by a corresponding switch 11. Each switch 9 will preferably be connected to operate simultaneously with a corresponding switch 11, whereby the operator, with a single movement, may close the circuit through predetermined sets of adjustable condensers 8-10. It will be readily understood that by opening the double pole double throw switches 5-5 and by closing the condenser switches 9 and 11, one condenser 8 (which will have been set to a predetermined value) will be substituted for the variable condenser 3, and one condenser 10 (which will have been set to a predetermined value) will be substituted for the variable condenser 4. The simple adjustable condensers 8-8-8 and 10-10-10 need only be relatively inexpensive, and for this purpose it is preferred to use the type known as semi-fixed, which type is characterized by the fact that the value of the condenser may be adjusted by the simple manipulation of a screw or the like. For purposes of economy of manufacture, therefore, it is preferred not to have the condensers 8-8-8 and 10-10-10 of an expensive type having indicating means for accurately indicating their capacities. An inexpensive means for conveniently setting the adjustable condensers 8-8-8 and 10-10-10 is illustrated in the set-up associated with the inductance 2. By reference to Figure 1 it will be noted that the connection of the circuit 7-7 with its double pole double throw switch 5 is controlled by the double pole double throw switch 12, which double pole double throw switch 12 is shown in position to connect said circuit 7-7 to its double pole double throw switch 5. The numerals 13-13 indicate a circuit cooperating with the double pole double throw switch 12 and the corresponding double pole double throw switch 5. As indicated above, the switches 5-5 are preferably connected to move in unison. When the variable condenser 3 is thrown out of cooperative relationship with the inductance 1 by reason of movement of the corresponding double pole throw switch 5, the variable condenser 4 may still be maintained in cooperative relationship with the inductance 2 by manipulation of a double pole double throw switch 12. When the double pole double throw switch 5 cooperatively associated with the inductance 2 is in its lowermost position as the parts are viewed in Figure 1, said inductance may be connected to the variable condenser 4 by moving the double pole double throw switch 12 to the right as the parts are viewed in Figure 1, or said inductance 2 may be connected to the circuit 7-7 by moving said double pole double throw switch 12 to the left as the parts are viewed in Figure 1.

In originally setting the simple adjustable condensers 8-8-8 and 10-10-10, a predetermined broadcasting station will be tuned in by means of the tuning condensers 3 and 4, the double pole throw switches 5-5 will be moved to their lowermost positions and the double pole double throw switch 12 will be moved toward the right as the parts are viewed in Figure 1. Under these conditions the adjustable condensers 8-8-8 will be in cooperative relationship with inductance 1 and variable condenser 4 will be in cooperative relationship with the inductance 2. With said variable condenser 4 in position for tuning in a predetermined broadcasting station, one of the adjustable condensers 8 will be manipulated until said broadcasting station is tuned in. With the tuning condenser 4 set for a different broadcasting station, another of the adjustable condensers 8 will be set for said other station. A plurality of broadcasting stations may be accommodated, depending upon the number of sets of adjustable condensers 8-8-8 and 10-10-10. After the adjustable condensers 8-8-8 have all been set for predetermined broadcasting stations, the double pole double throw switch 12 will be moved to its left-hand position as the parts are shown in Figure 1, throwing the variable condenser 4 out of circuit and throwing the circuit 7-7 into cooperative relationship with inductance 2. With one of the adjustable condensers 8 in circuit, a corresponding condenser 10 will be set to bring in the corresponding broadcasting station. A similar procedure will be carried out with each of the other adjustable condensers 8 and their corresponding adjustable condensers 10, until all of the sets of adjustable condensers 8-10 have been brought into proper tuning relationship with different broadcasting stations.

Figure 1 shows the present invention as applied to a radio receiver having two tuning elements. Associated parts of a receiver have been indicated generally by the numeral 14, but inasmuch as said associated parts form no part of the present invention a description thereof is deemed to be unnecessary.

Figure 2 illustrates the present invention as applied to a radio receiver having three tuning elements. The features relating to the present invention will be clear from the description of Figure 1, the features relating to the present invention added in Figure 2 being the same as those associated with the inductance 2 in Figure 1, said added features having similar reference numerals to corresponding parts in Figure 1, but with the letter "A" added thereto. The inductances in Figure 2 are indicated by the numerals 1, 2 and 2A, and the corresponding condensers are indicated by the numerals 3, 4 and 4A. In Figure 2 the double pole double throw switches 5-5-5 are preferably connected to

operate in unison. The double pole double throw switches 12 and 12A, however, will preferably be independently operable, whereby it will not be necessary to attempt to adjust simultaneously the adjustable condensers associated with two of the tuning elements. The associated parts of the three tuner circuit illustrated in Figure 2 have been indicated by the numeral 15.

As will be understood from the discussion of Figure 1 appearing above, a predetermined broadcasting station may be tuned in by manipulation of the three variable condensers 3, 4 and 4A, after which the double pole double throw switches 5—5—5 may be thrown downwardly. One of the adjustable condensers 8 will then be adjusted to tune in said predetermined broadcasting station. In similar manner, all of the adjustable condensers 8 are set for predetermined broadcasting stations. After all of the variable condensers 8—8—8 have been set for different broadcasting stations, the double pole double throw switch 12 will be thrown to connect the circuit 7—7 in cooperative relationship with the inductance 2, the switch 12A being left in position to connect the variable condenser 4A and the inductance 2A. Each of the adjustable condensers 10—10 will then be adjusted to tune in the same stations for which the corresponding condensers 8—8—8 were set. Thereafter, the double pole double throw switch 12A will be moved to position to connect the circuit 7A—7A to the inductance 2A, after which the adjustable condensers 10A—10A—10A will be adjusted to tune in the same stations to which the corresponding condensers 8—8—8 and 10—10—10 have been adjusted.

It will be clear that the radio receiver may be operated in the ordinary manner, if preferred, by merely throwing the double pole double throw switches 5—5 to their upper positions as the parts are viewed in Figures 1 and 2. If the convenience of the predetermined settings is desired, the operator of the set may, after the adjustable condensers 8—8—8, 10—10—10 and 10A—10A—10A have once been adjusted, with a simple movement simultaneously operate a predetermined set of switches 9, 11 and 11A, whereby the corresponding condensers 8, 10 and 10A are in circuit to tune in a predetermined broadcasting station. Similar operation of other sets of switches 9, 11 and 11A will connect in circuit other sets of condensers 8, 10 and 10A to bring in other broadcasting stations.

Many modifications of the present invention will occur to those skilled in the art. It is intended to cover all such modifications that fall within the scope of the appended claims.

What is claimed is—

1. In a radio receiver, a plurality of variable tuning elements, circuits associated with

said variable tuning elements, each of said circuits containing a plurality of adjustable tuning elements, switch means operable in unison for selectively rendering operative said variable tuning elements or their corresponding circuits, and means for rendering operative certain of said variable tuning elements regardless of the connections of said other variable tuning elements in circuit for permitting the adjustment of the adjustable tuning elements in each of said circuits independently of the other variable tuning elements or the other adjustable tuning elements.

2. In a radio receiver, a plurality of variable tuning elements for tuning in any preferred frequency within the limits of said receiver, a plurality of adjustable tuning elements associated with each of said variable tuning elements, switch means for substituting said adjustable tuning elements for said variable tuning elements, and auxiliary switch means associated with certain of said variable tuning elements, each of said auxiliary switch means being adapted to render operative its corresponding variable tuning element regardless of the operation of said first mentioned switch means.

3. In a radio receiver, a plurality of inductances, a variable tuning element cooperatively associated with each of said inductances, a plurality of circuits, each cooperatively associated with a corresponding one of said inductances, switch means cooperatively associated with each of said inductances, said switch means being operable in unison for selectively controlling the connection of said inductances to said variable tuning elements or to said circuits, each of said circuits including a plurality of adjustable tuning elements, said adjustable tuning elements being adapted to be thrown into or out of circuit in sets corresponding to said variable tuning elements, and switch means associated with one of said inductances for connecting said inductance to its corresponding variable tuning element regardless of the operation of said first mentioned switch means and regardless of the operation in sets of said adjustable tuning elements.

4. In a radio receiver, a plurality of variable tuning elements, a plurality of circuits each containing a plurality of adjustable tuning elements, said circuits being adapted to replace said variable tuning elements in the operation of said receiver, switch means for selectively rendering operative said variable tuning elements or said circuits, and other switch means cooperatively associated with one of said variable tuning elements for controlling the operativeness of its corresponding variable tuning element regardless of the operativeness of any of the other of said variable tuning elements, each of said circuits being provided with a plurality of switches

for selectively connecting said adjustable tuning elements into operative relationship with said circuit, corresponding switches in said circuits being connected to operate in unison.

5. In a radio receiver, a plurality of variable tuning elements, a plurality of circuits each containing a plurality of adjustable tuning elements, said circuits being adapted to replace said variable tuning elements in the operation of said receiver, switch means for substituting said circuits for said variable tuning elements in the control of said receiver, and switch means cooperatively associated with certain of said variable tuning elements for controlling the operativeness of its corresponding variable tuning element regardless of the operativeness of any of said other tuning elements or said adjustable tuning elements associated with said other tuning elements, each of said circuits being provided with a plurality of switches for selectively connecting said adjustable tuning elements into operative relationship with said circuit, corresponding switches in said circuits being connected to operate in unison.

6. In a radio receiver, a plurality of variable tuning elements, circuits associated with said variable tuning elements, each of said circuits containing a plurality of adjustable tuning elements, switch means operable in unison for selectively rendering operative said variable tuning elements or their corresponding circuits, and means for rendering operative certain of said variable tuning elements regardless of the connections of said other variable tuning elements in circuit for permitting the adjustment of the adjustable tuning elements in each of said circuits independently of the other variable tuning elements or the other adjustable tuning elements, each of said circuits being provided with a plurality of switches for selectively connecting said adjustable tuning elements into operative relationship with said circuit, corresponding switches in said circuits being connected to operate in unison.

Signed at Chicago, Illinois, this 24th day of August, 1928.

JOHN J. CHRISTOFFEL.
